UNITED STATES PATENT OFFICE.

EARL E. EICKMEYER, OF DAYTON, OHIO, ASSIGNOR TO THE DAYTON PUMP & MFG. COMPANY, OF DAYTON, OHIO, A CORPORATION OF OHIO.

GASOLINE PUMP.

Application filed April 13, 1927. Serial No. 183,422.

My invention relates to gasoline pumps and particularly to the housing for visible dial indicating mechanism.

It is the object of my invention to provide a semicircular cover glass conforming to the general outline of the pump housing while at the same time permitting of the observation of the dial and the hand from a position to one side of the dial plate and hand.

It is a further object to provide a semicircular plate which will make it possible to secure a large area between the plate and the dial face for the introduction of artificial light to illuminate the dial plate.

Referring to the drawings,

Fig. 1 is a front elevation of a complete pump showing in dotted lines the position of the artificial illumination;

Fig. 2 is a side elevation of the dial plate, cover glass and cover glass housing;

Fig. 3 is a front elevation thereof;

Fig. 4 is a section on the line 4—4 of Fig. 3.

Referring to the drawings in detail, 1 is a casing, preferably of such a shape as to have a plurality of flat panels. This case is provided with an opening on the front and rear thereof, adjacent each of which openings is located a dial plate 2 on the bracket 4 adjacent the shaft 3 which carries the pointer 5. 6 indicates the setting button of the usual character which is located in the curved glass plate 7 of my invention. This plate is mounted in a frame consisting of a bezel 8, a frame portion 9 and a retaining shoulder 10. The frame in horizontal section is semicircular to conform with the semicircular glass 7. The glass is held in position by the resilient retaining ring 11.

The frame is mounted on an escutcheon plate 12 which is attached by the screws 13 to the casing 1. Thus the curved glass is suitably supported in a curved frame which

is mounted through its escutcheon plate and sidewalls by flat surfaces 14 on the flat panels of the casing 1. The casing 1 being angular in section. The dial 2 is spaced within the casing leaving a space for the lamp 15 to cast its rays between the dial face and the glass.

As the person seated in an automobile, the rear tank of which is being filled with gasoline, is not directly opposite to the dial but to one side thereof, the very bright interior illumination of the dial and the curved glass permits of a vision from one side of the pump from the front seat of the automobile so that the indicating mechanism can be observed.

The frame 8 serves as a guard and the bezel serves as a reinforcement and an attaching member to conform to the angular shape of the casing of the pump.

The use of the curved glass prevents light reflections which make it difficult to read the dial from one side as the observer is looking more nearly through the glass at right angles thereto no matter what his position may be to the glass due to its curvature.

It will be understood that I desire to comprehend within my invention such modifications as may be necessary to adapt it to varying conditions and uses.

Having thus fully described my invention, what I claim as new and desire to secure by Letters Patent is:—

An article of manufacture for use in connection with gasoline dispensing pumps consisting of an angular bezel plate, a frame member mounted thereon, means to retain a glass in said frame member and a glass mounted therein having a vertical face transversely curved.

In testimony whereof, I affix my signature.

EARL E. EICKMEYER.
